UNITED STATES PATENT OFFICE.

LOUIS B. CASTANO, OF CHAPARRA, CUBA.

SAFETY ATTACHMENT FOR CARS.

1,289,653.

Specification of Letters Patent. Patented Dec. 31, 1918.

Application filed August 9, 1918. Serial No. 249,131.

To all whom it may concern:

Be it known that I, LOUIS B. CASTANO, a citizen of the Republic of Cuba, residing at Chaparra, Republic of Cuba, have invented 5 new and useful Improvements in Safety Attachments for Cars, of which the following is a specification.

This invention relates to a safety device for preventing the derailing of railway cars.

10 The primary object of the invention is to produce a device of this character which may be readily attached to the axle of any ordinary railway car and which is so arranged with respect to the rail over which 15 the car wheels travel as to engage and grip the said rails, should the car be subject to a side or tilting movement, but which is altogether out of engagement with the rail to permit of the free travel of the car there- 20 over, under all normal conditions.

It is a further object of the invention to produce a device of this character which shall be of an extremely simple nature, cheap to manufacture, easily applied and 25 thoroughly efficient for the purpose devised.

Other objects and advantages will present themselves as the nature of the invention is better understood, reference being had to the accompanying drawings, in which,

30 Figure 1 is a side elevation illustrating the application of the improvement.

Fig. 2 is a sectional view approximately on the line 2—2 of Fig. 1.

Fig. 3 is a sectional view approximately 35 on the line 3—3 of Fig. 2, looking in the direction of the arrows.

Fig. 4 is a perspective view of the improvement.

In the drawing, 5 designates a rail, 6 a car 40 wheel designed to travel over the rail. The axle for the wheel 6 is indicated by the numeral 7, and my improvement broadly by the numeral 8. The member 8 may be constructed of some hard tough material, such 45 as harveyized steel or the like, and comprises two spaced sleeves 9 and 10 respectively which, if desired, may be in the nature of split members so as to facilitate the arrangement of the same upon the axle 7, or when 50 the said sleeves are solid, suitable binding elements may be passed therethrough to rigidly lock the same to the axle. The sleeve 9 is formed upon the outer face of the improvement, and this face comprises prefer- 55 ably three spaced arms, the inner arm being indicated by the numeral 11 and the outer

arms by the numerals 12. The outer arms are inclined outwardly from the inner arm and from the sleeve, but the ends of the said outer arms are vertically straight, or in a 60 line with the end of the inner arm 11. These arms, adjacent the outer ends thereof are connected by webs 13, and each of the arms, upon its lower edge is provided with an inwardly extending lug 14. The lugs 14, as 65 clearly illustrated in Fig. 2 of the drawing, are designed to be arranged below the tread of the rail 5, upon the outer side of the said rail, but out of contact with both the head and the web of the rail. 70

The inner sleeve 10 is formed with a pair of outwardly extending angularly disposed rod members 15, the same being arranged over the top of the rail 5 and connected to the outer arms 12 of the device. 75

It is, of course, to be understood that my improvement is to be arranged upon the opposite sides of the rails, that is, attached to each of the axles, and as the lugs 14 are arranged in close proximity to the under face 80 of the ball of the rails, it will be apparent that any lateral or tilting movement of the car will bring the said lugs into contact with the under faces of the balls of the rails, and consequently, prevent the derailing of the 85 car.

Having thus described the invention, what I claim is:

1. A safety attachment for cars comprising a member including two spaced sleeves 90 arranged upon the axle of the car to the opposite sides of the wheel thereof, arms depending from the outer sleeve, inwardly extending lugs on the arms arranged in the fish-plate space but out of contact with the 95 rail on which the wheel travels, and connecting means between the said arms and the inner sleeve.

2. In a safety device for railway cars, a member arranged upon the outer end of the 100 car wheel axle and having a depending portion, the lower edge of which being inturned to provide lugs, the said lugs being arranged in the fish-plate space but out of contact with the rail on which the wheel travels, an 105 inner member secured on the axle, and brace means between the said inner member and the outer member of the device.

3. A safety attachment for cars comprising two spaced sleeves each arranged upon 110 the axle of the wheel and one adjacent the outer face of the wheel, means for securing

the sleeves to the axle, the outer sleeve having spaced arms depending therefrom, the outer arms being arranged angularly with respect to the inner arms, whereby the said 5 outer arms, adjacent the ends thereof, are spaced outwardly from the tread surface of the car wheel, ribs connecting the arms, said arms having their ends provided with in-turned lugs arranged in the fish-plate space

of the rail on which the wheel travels but out 10 of contact with the said rail, and angularly disposed rod members formed with the inner sleeve and connecting the outer arms at points between the periphery of the wheel and the tread surface of the rail.

15 In testimony whereof I affix my signature.

LOUIS B. CASTANO.
